UNITED STATES PATENT OFFICE.

JOHN H. WIESTNER, OF PHILADELPHIA, PENNSYLVANIA.

HORSESHOE.

1,109,495.

Specification of Letters Patent.

Patented Sept. 1, 1914.

Application filed January 14, 1914. Serial No. 812,097.

To all whom it may concern:

Be it known that I, JOHN H. WIESTNER, a citizen of the United States, residing at Philadelphia, in the county of Philadelphia and State of Pennsylvania, whose post-office address is 3556 Frankford avenue, have invented certain new and useful Improvements in Horseshoes; and I do hereby declare the following to be a full, clear, and exact description of the invention, such as will enable others skilled in the art to which it appertains to make and use the same.

This invention is a horse-shoe of that type which provides a metallic shoe having a non-metallic tread to prevent the animal from slipping on the roadway.

The objects of the invention may be stated as follows: to provide, first, a shoe having an elastic tread which will prevent slipping of the animal on wet or slippery surfaces, the elastic tread serving to bear a part of the wear which would ordinarily be imposed upon the shoe; second, a shoe which will give a full bearing at all points to the foot 25 of the animal, and especially at the heel portion thereof; third, a shoe which is especially adapted for animals having tender feet, and which will at the same time decrease the noise of an animal passing over paved streets; and fourth to so construct 30 the metallic and non-metallic elastic tread of the shoe that the tread may be readily removed from the metallic part of the shoe to permit the shoe to be heated and shaped to fit the foot of the animal, and thereafter applied to the animal.

Furthermore, the invention aims to obviate the necessity of frequently applying new shoes to the animal in the winter seasons 40 to furnish sharp toe and heel calks.

The invention is characterized by the employment of a metallic shoe having a channel extending around the toe portion thereof substantially of the width of the 45 tread or face of the shoe, the channel terminating at the heel of the shoe into broad bearing chambers within which are placed retaining devices. Within the channel and these chambers is placed a fibrous tread 50 substance, such as rope of a size to substantially fill the cavity in the face of the shoe, the fibrous substance being twisted or coiled around the retaining devices to provide a broad cushioned bearing surface at the heel 55 of the shoe.

In the accompanying drawings, Figure 1

is a plan view of the face of the shoe with the cushioned tread thereon. Fig. 2 is a plan view of another embodiment of the invention with the tread substance removed. Fig. 60 3 is a sectional view through the shoe of Fig. 1. Fig. 4 is a sectional view through the shoe of Fig. 2.

In the embodiment of the invention illustrated in Figs. 1 and 3, the metallic portion 65 of the shoe may be of any desired material, and may be made in any suitable manner such as by casting or drop forging. The shoe may be of the ordinary width at the toe 5, but is preferably broadened at the 70 heel terminals thereof, one of said terminals 6 being shown in Fig. 1 as of greater area than the other terminal 7, although this feature of construction may depend entirely upon the needs of the animal, and both terminals 6, 7 may be of the same width and length. The tread or face 8 of the shoe 75 may be provided with a deep channel 9 which extends from one heel terminal 6 around the toe 5 to the other heel terminal 7, the channel opening into broad chambers 10 of the heel terminals 6, 7. The channel 9 and chambers 10 are of such area, that they leave comparatively narrow walls 11 around the shoe, through which walls the attaching 80 nails may be inserted. Within the chambers 10 there is positioned a retaining device, shown in Figs. 1 and 3 as an upstanding bar 12 integral with the shoe, the bar extending longitudinally of the elongated chamber 10 85 of the heel terminal. These chambers and terminals are illustrated as substantially ovoid in shape. Within the channel 9 and chambers 10 there is positioned a fibrous tread 13, which may be of any suitable 90 substance, such as rope, and this tread is forced into the channel 9 of the shoe body and heel in frictional engagement therewith until the fibrous tread 13 combines with the face 8 to form a combined tread for the shoe. The tread 13 is preferably of a thickness to 95 fit snugly into the channel 9 and to be passed around the outer part of the retaining bar 12, and thence doubled upon itself, as at 14, and thence brought into contact with the inner face of the bar 12, and thence extended until the end 15 thereof engages the main body portion of the fiber, as will be understood by an inspection of Fig. 1. If desired the retaining devices may be provided with 100 flared outer edges as at α in Fig. 3 which 105 will serve to retain the ropes within the 110

cavity of the shoe. This broad fibrous tread at the heel terminal of the shoe affords comfort to the animal in traveling, and at the same time gives great stability.

5 In Figs. 2 and 4, the shoe is shown provided with retaining flanges 16 at the toe portion thereof, and with a plurality of upstanding studs 17 in the chamber 10 of the heel terminal, the studs permitting of the 10 winding of the fibrous material with greater facility, and at the same time serving to retain the soft tread in the shoe when in use. It is obvious that the flanges 16 may be omitted if desired. The channel 9 and chambers 15 10 may be provided with a rounded lower surface, as shown in Fig. 3 to accommodate the fibrous material, or the studs 17 may be tapered from their connected base to their apex, as illustrated in Fig. 4, and the edges 20 18 of the walls may be thickened as in Fig. 4 and bent inwardly to serve as retaining means for the rope. The shoe may be applied to the hoof of the animal in the usual manner by passing the usual nails through 25 suitable holes 19 provided in the shoe, into the hoof. A fibrous tread is selected in lieu of other resilient materials, such as rubber, or in lieu of a filling composition such as cement, because of the freedom from wearing 30 smooth and becoming somewhat useless on wet pavements, and also in view of the freedom with which the fibrous material may be applied to the shoe, as distinguished from the cast or vulcanized shoe fillings. It is to be 35 understood also that the combined area of the heel terminals is equal to substantially a half of the full tread of the animal's foot, the inner faces of the ovoidal terminals substantially conforming to the frog of the animal's foot.

Having thus described my invention what I claim as new and desire to secure by Letters Patent, is:

1. A horse-shoe comprising a metallic 45 member having broadened heel terminals, the shoe being provided with a channel throughout the face thereof, and a fibrous tread adapted to be fitted in the channel of the metallic member and doubled upon itself

at the heel terminals, the ends of the fibrous tread terminating in engagement with the main body thereof.

2. A horse-shoe comprising a metallic member having a narrow tread and broadened heel terminals, each terminal being provided with a chamber, and said chambers being connected by a channel extending around the face of the shoe, a fibrous tread adapted to be packed within the channel and the terminal chambers, and means within the terminal chambers and disconnected from the metallic tread to retain the fibrous material therein.

3. A horse-shoe comprising a metallic member having broadened heel terminals, the face of the shoe being provided with a groove which extends from a chamber in one heel terminal to a chamber in the other heel terminal, upstanding retaining members integral with the metallic portion of the shoe and positioned substantially at the central portion of the chambers of the heel terminals, to leave a space around said retaining members, and a fibrous tread adapted to be packed in the groove and to be wound around said upstanding retaining members to fill said chambers.

4. A horse-shoe having a plurality of channeled ovoidal heel terminals, one of said terminals being of greater area than the other, the face of the shoe being channeled out to connect the channels of the heel terminals, an integral upstanding retaining device positioned within each of the ovoid terminals, opposed retaining flanges positioned at a point over the channel intermediate the heel terminal and a fibrous tread secured within the channel and placed into engagement with the flanges and the upstanding retaining members to present a broad cushioned tread to the shoe.

In testimony whereof, I affix my signature, in presence of two witnesses.

JOHN H. WIESTNER.
